6-28-1836

William Moore & John Hascall of Calumet Co. Mich:
Letters Patent

The Schedule referred to in these Letters Patent and making part of the same containing a description in the words of the said William Moore and John Hascall themselves of their improvement in the Harvesting machine for reaping, threshing and winnowing grain at one operation.

To all whom it may concern. Be it known that we William Moore and John Hascall of Calumet County Michigan have invented certain improvements in the machinery for Harvesting grain by means of which wheat or other grain may be cut, threshed, and winnowed, each of these operations going on simultaneously. The whole of the necessary motions being derived from the animal or other power employed to propel the machine, and we do hereby declare that the following is, a full and exact description thereof, reference being had to the drawings which accompany and make a part of this Specification.

In describing this machine, the dimensions which . . . we shall give are taken from one which we have constructed, and which we have found to answer well in practice. While we manifest however that these dimensions are not to be considered as absolute, but merely as an approximate guide to others any variation in this particular not changing the character of the machine.

The mode of gearing also and the number of teeth in the wheels employed the substitution of sprogs, or belts, for geared wheels, may be resorted to according to the fancy or preference of the person constructing it.

A. In fig. is the frame which is to support the whole structure and is, seventeen feet long and fifteen broad from outside to outside. B. are uprights attached to the frame or platform and connected at top by the cap piece C. The wheels D bear upon the ground like cast wheels and by their motion give motion to the cutting, threshing and winnowing apparatus whenever the machine is drawn forward. These wheels are seven feet in diameter and E. is the roller of that which carries the grain.

is broad and should it be found to slide on the ground is to be armed with spikes projecting from its rim which will prevent this from taking place. The quidgong of this wheel is fixed firmly in its hub and is set on a seat, in the uprights B. The other wheel D turns on an iron axle, firmly attached to one of the uprights B. E is a cog wheel fixed on a pinion such as in the wheel and gears into a pinion F about eleven inches in diameter. The wheel D is attached to the spokes of the wheel D and the quidgong of the pinion may be supported by a stud or brace attached to the frame through the intermediate of this pinion the other part of the machinery receive their motion and as it is necessary to allow the machine to be drawn forward while the operating parts are at rest this pinion is disengaged and into gear by means of a forked lever G in a manner well known to mechanist. H is a band wheel on the same shaft with the pinion F and is three feet in diameter. I is what we denominate the gathering cylinder to be presently described. This gathering cylinder is turned by a band H as seen in the drawing which band must be crooked when the pinion F is geared upon the outside of the wheel D when the machine is drawn by such small force the shaffer pole being attached to the frame at K is connected with the four running blocks L about ten feet in diameter on a small sled or skagh may be substituted for these four running blocks.

Fig. L shows the cutting part of the apparatus which in fig 1 is hidden by the gathering cylinder. M, M are pieces denominated fingers which may be of wood two feet in length one inch thick and three or four inches deep. They project from the front of the platform and are pointed so as readily to admit the stalks or stems of the grain to pass between them into the cutters or cutters. The cutters may be made as follows. There may be a fixed plate of steel extending along and projecting from the front of the platform so as to project immediately under the blocks L on top of the inner ends of the fingers having pointed teeth, resembling saw teeth with a second steel plate furnished with similar teeth made to vibrate longitudinally with former by means of a crank or otherwise so as to cut the stalks or stems between them the vibrating teeth may be made to turn on pins individually like the sciss-

one ~~sliding~~ ^{sliding} and giving motion to the whole. This mode of constructing the cutters somewhat resembles those already in use for cutting grain. (The do not however prefer either of these modes for constructing the cutters believing the following, which is, of course ~~more~~ ^{more} ~~inventive~~, is better.)

The fixed toothed plate N N may be made as described with saw teeth and against this near the edge of the teeth a straight plate of steel is made to vibrate longitudinally. The cutting edge of this plate is like that of a sickle, and by aid of the gathering cylinder. This cutter affects the grain ~~more~~ ^{more} ~~intended~~ ^{very} ~~perfectly~~. When the sickle edge vibrates through the fingers, the fixed plate a. b. l. may be dispensed with.) The gathering cylinder I is four feet in diameter, twelve feet in length. From the surface project a considerable number of pointed teeth of wood or metal which teeth may be from two to six inches in length, from twelve to twenty four rows of such teeth continuing a length the cylinder four or six inches in diameter will be found sufficient. The cylinder is so placed that the ends of the teeth project forward, nearly as far forward as the points of the fingers. They consequently catch hold of the heads of the grain bending it down carrying it between the cylinder and the front of the platform and holding it against the cutter. A concave or formed under this cylinder allowing the teeth of the cylinder to come nearly into contact therewith.

As the cut grain is conducted back by the gathering cylinder it is delivered on an endless revolving apron C. O. This revolving apron passes round shafts in the usual manner. The shafts are constructed as may be seen in the model one in both of them shafts being driven by suitable gearing. To insure the regular motion of the apron and to keep it in place its edges are furnished with sharp, or teeth of leather or other suitable material preferably preferable with holes, which pass over the teeth of guide wheels in the end of the revolving shafts, which shafts are constructed of round bars of iron and between the guide wheels are fitted with large rollers, from four to eight inches in diameter, one foot in length which serve to regulate the centre of the apron. The grain is carried upon the revolving apron to the threshing apparatus which is constructed with a cylinder & sides ^{which} are coupled together, with cover constructed in the usual manner.

He drives the threshing cylinder by means of a spur wheel α on the same shaft with the band wheel B , and pinion B' . The gearing being such as to give to the threshing cylinder the required velocity say the first being moving at the rate of about five thousand feet per minute when the horses travel at their usual speed. The threshed grain and straw are thrown out from between the cylinder and concave at an elevation of forty five degrees, and strike against a concave recessing placed above them, for the purpose of causing them to fall upon a sieve or a receding screen $R R$ made of nailing, passing around rollers, which nailing screen allows the grain to fall through and deliver the straw at the back of the machine. The trough into which the grain falls has a concave bottom for a reason which will be apparent, instead of the nailing the rollers may have numerous grooves turned in them to receive bands of cruds. The grain as it falls through into the concave trough is received by a receding fan, and the shaft furnished by spiral flights or steps, which turn near the bottom of the concave trough cause the grain to one end where it may be raised by a rafter and be poured out into bags or bags to be loaded by an assistant on the platform. These parts may be ground or as to be driven by the spur wheel α , as will be obvious to any competent machinist. R is a lever to move the gathering cylinder cutting apparatus &c. when any objection to the height of the grain renders it necessary desirable to do so. The timber S to which the four wheels and pole are attached is separate from and extends under the main frame to which it is hinged at K near the wheel D . A person standing upon the platform and supporting the lever R will therefore raise the parts mentioned. The stand, which supports its fulcrum being attached to the timber S .

If suitable teeth for threshing are put into the gathering cylinder and the concave the said cylinder will answer the double purpose of gathering and threshing the grain, or if said cylinder is covered with fine wire mesh iron and its concave is shielded with the same it will also answer the purpose, and in either case the other threshing apparatus may be suspended with. Having thus fully described the construction and operation of the said machine I do solemnly declare that

we do not rest our claim to invention upon any of the parts thereof taken individually, with the exception of the gathering cylinder and double edged roller operating in the manner and for the purpose described. We also claim the manner in which we have combined them with the other parts of the machinery so as to carry on the cutting threshing and cleaning of the grain simultaneously.) Not intending however to limit ourselves to the precise manner of arranging the gearing and other minor parts, as having others but to vary the same as we may think proper while the mode of action remains substantially the same.
